Charles W. Beamer

By Clarence O'Brien
Attorney

UNITED STATES PATENT OFFICE.

CHARLES W. BEAMER, OF SPRING GARDEN, CALIFORNIA.

FRONT-AXLE GAUGE.

Application filed March 9, 1927. Serial No. 173,978.

The present invention relates to improvements in gauges and has reference more particularly to a device adapted for setting front axles.

5 One of the important objects of the present invention is to provide a front axle gauge which may be readily and easily adjusted or set to any predetermined position depending upon the angle at which the spindle bolt holes are to be disposed with respect to the front axle, the gauge including means for disposition through the spindle bolt holes.

10 A further object of the invention is to provide a front axle gauge of the above-mentioned character which is simple in construction, inexpensive, and furthermore well adapted for the purposes for which the same is designed.

15 20 Other objects and advantages of the invention will become apparent during the course of the following description.

In the accompanying drawing forming part of this specification and in which like numerals are employed to designate like parts throughout the same:

25 Figure 1 is a side elevation of the gauge embodying my invention showing the same in use,

30 Figure 2 is an enlarged side elevation showing more specifically the construction of the pointer arm and the spindle bolt hole engaging means associated therewith,

35 Figure 3 is a top plan view, and

40 Figure 4 is a sectional view taken approximately on the line 4—4 of Figure 3, showing the pivotal connection between the blade and the outer end of the pointer arm.

45 In the drawing, wherein for the purpose of illustration is shown the preferred embodiment of my invention, the numeral 1 designates an elongated horizontally disposed blade, the same being adapted for disposition above the front axle A in the manner as clearly shown in Figure 1 and for a purpose hereinafter to be more fully described.

50 A pointer arm 2 is detachably and pivotally secured at its outer end on one side of the blade 1 at the outer end thereof as illustrated at 3. The pivot forming pin 3 is threaded at its respective ends and wing nuts 3' are threaded thereon for securing the parts in assembled relation. A pointer head 4 is formed on the inner end of this pivoted arm and the pointed end of the head is

adapted for cooperation with suitable graduations 5 arranged on the intermediate portion of the blade 1 on one side thereof in the manner clearly illustrated in Figure 2. 60

An arcuate-shaped slot 6 is formed in the pointer head 4 and extended through this slot is the threaded end of a bolt 7 which is carried by the intermediate portion of the blade 1. A thumb nut 8 is threaded on the free end of this bolt and is adapted to engage the outer face of the head 4 for securing the pointer arm in any set position with respect to the blade so that the arm will not swing on its pivot. This will be further 70 explained later in the description of the operation or use of the device.

Also forming a part of the present invention is the spindle bolt hole engaging means, the same comprising a relatively short flat shank 9 which carries on its lower end an inverted conical head 10. This shank is disposed at right angles to the pivoted end of the pointer arm 2 and is rigidly attached thereto by the rivets 11. The pivot pin 3 80 which connects the arm 2 to the blade 1 also extends through the shank 9 in the manner clearly illustrated in Figs. 2 and 3. The smaller end of the inverted conical-shaped head 10 is formed with a threaded socket 12 85 in which is threaded the upper threaded end of a vertically disposed rod 13. Any suitable means may be provided for securing the upper threaded end of the rod 13 from accidental displacement from the internally 90 threaded socket 12 such as is shown at 14.

The lower end of the vertical rod 13 is threaded as illustrated at 15 and arranged thereon is the conical-shaped head 16, the same being provided with an internally 95 threaded bore to permit the same to be threaded onto the lower threaded portion 15 of the rod 13. Suitable thumb nuts 17 are formed on the bottom of the lower conical head 16 to facilitate rotation of the same 100 on the lower threaded portion 15 of the rod 13.

In use, the thumb nut 8 is loosened and the pointer carrying arm 2 is swung on its pivot 3 so that the spindle bolt hole engaging means which is disposed at right angles with respect to the pointer arm may be set in any predetermined position. The graduations 5 provide means whereby the proper angle may be ascertained at which the spindle bolt engaging means is disposed with respect to the horizontal blade 1 and when

the parts have been properly set, the thumb nut 8 is moved into engagement with the outer side of the head 4 thus securing the arm 2 against swinging movement with respect to the blade 1.

The lower conical head 16 is removed from the threaded end 15 of the rod 13 and this rod is inserted downwardly through spindle bolt holes formed in the upper and lower spindle arms B and C respectively of a front axle A and the inverted conical head 10 will be seated in the upper spindle bolt hole. The lowermost conical head is then threaded on the lower threaded end 15 of the rod 13 so that the same will enter the lower spindle bolt hole and by reason of the heads being conical, the same will be properly centered in the spindle bolt holes and with the parts arranged as shown in Figure 1, a person can readily ascertain whether or not the front axle is properly set and this by way of noticing whether or not the horizontal blade 1 is properly spaced from both of the spring saddles or seats D formed on the upper face of the front axle A.

If the blade 1 is not equally spaced from both of the saddles D, then the front axle must be bent so that the same will be disposed parallel to the blade.

It will be thus seen from the foregoing description that I have provided a front axle gauge which may be readily and easily set and furthermore attached to the front axle. This gauge will at all times be positive and efficient in carrying out the purposes for which it is designed and the simplicity of its construction enables the several parts to be readily and easily adjusted.

The detachable blade 1 has graduations provided on its opposite side adjacent both of the longitudinal edges thereof, whereby the blade may be used as a straight edge when the tool is used as a square and also the blade may be used as a circumference measure.

What I claim as new is:—

1. A front axle gauge comprising an elongated blade, a pointer arm pivotally secured at one end to the blade at one end thereof, means for securing the other end of the arm to the blade at any predetermined angle, and spindle bolt hole engaging means fixedly secured to the pivoted end of the pointer arm and disposed at right angles thereto.

2. A front axle gauge comprising a blade, a pointer arm pivotally secured at one end to the blade at one end thereof, means for securing the other end of the arm to the blade at any predetermined angle, and spindle hole engaging means fixedly secured

to the pivoted end of the pointer arm and disposed at right angles thereto, said last-mentioned means comprising an inverted conical-shaped head attached to the pivoted end of the arm, a vertical rod secured at its upper end to the lower portion of the inverted conical head, and an additional conical head adjustably secured on the lower end of the rod.

3. A front axle gauge comprising a blade adapted for disposition above a front axle, a pointer arm pivotally secured at one end to the blade at one end thereof, a member secured rigidly to the pivoted end of the arm and disposed at right angles thereto, an inverted conical head for engagement with the upper spindle bolt hole of the front axle depending from said member, a vertical rod secured at its upper end to the lower end portion of the inverted conical head, the lower end of said rod being threaded, an additional conical-shaped head formed with a threaded bore for threaded engagement on the lower end of the rod and adapted to engage in the lower spindle bolt hole, and means for securing the pivoted pointer arm and the right angularly disposed spindle bolt hole engaging means in any set position with respect to the blade.

4. A front axle gauge comprising a blade adapted for disposition above a front axle, a pointer arm pivotally secured at one end to the blade at one end thereof, a shank member secured rigidly to the pivoted end of the arm and disposed at right angles thereto, an inverted conical head for engagement with the upper spindle bolt hole of the front axle depending from said shank member, a vertical rod secured at its upper end to the lower end portion of the inverted conical head, the lower end of said rod being threaded, an additional conical-shaped head formed with a threaded bore for threaded engagement on the lower end of the rod and adapted to engage in the lower spindle bolt holes, and means for securing the pivoted pointer arm and the right angularly disposed spindle bolt hole engaging means in set position with respect to the blade, said means comprising a bolt extending through the intermediate portion of the blade, the other end of the pointer arm being formed with an arcuate slot through which the free end of the bolt extends, and a thumb nut threaded on the bolt and adapted to engage the outer side of the aforementioned other end of the pivoted arm for securing the same against the blade.

In testimony whereof I affix my signature.
CHARLES W. BEAMER.
